FLOCKED TEXTILE FABRIC

Natalie Leavy, Clifton, N.J., assignor to Decorative Fabrics Company Incorporated, Pawtucket, R.I., a corporation of Rhode Island

Filed Feb. 12, 1960, Ser. No. 59,383

Term of patent 14 years

(Cl. D92—1)

The figure is a plan view of a flocked textile fabric showing my new design.

The design unit is contained between the dot and dash lines, which unit is repeated in regular succession as indicated by the extensions beyond the unit boundaries.

I claim:

The ornamental design for a flocked textile fabric, as shown and described.
